DESIGN FOR A HAIR ORNAMENT

Siegfried Behr, Flushing, N. Y.

Application July 14, 1945, Serial No. 120,709

Term of patent 14 years

(Cl. D86—10)

To all whom it may concern:

Be it known that I, Siegfried Behr, a citizen of the United States, residing at Flushing, county of Queens, and State of New York, have invented a new, original, and ornamental Design for a Hair Ornament, of which the following is a specification, reference being had to the accompanying drawing, forming part thereof.

Fig. 1 is a perspective view of a hair ornament embodying my new design.

Fig. 2 is a top plan view thereof.

I claim:

The ornamental design for a hair ornament, as shown,

SIEGFRIED BEHR.
